United States Patent Office

Des. 177,981
Patented June 12, 1956

177,981

VASE OR SIMILAR ARTICLE

George T. James, San Fernando, Calif., assignor to Glad-ding, McBean & Co., Los Angeles, Calif., a corporation of California

Application November 28, 1955, Serial No. 39,062

Term of patent 14 years

(Cl. D29—28)

Fig. 1.

Fig. 2.

Fig. 4.

Fig. 3.

Fig. 1 is a front elevational view of a vase or similar article showing my new design;

Fig. 2 is a side elevational view thereof;

Fig. 3 is a side perspective view thereof; and

Fig. 4 is a side perspective view thereof as seen from a position opposite to Fig. 3.

I claim:

The ornamental design for a vase or similar article, substantially as shown.
